Reg. 2 Milton M. Bragby, Inventor
By J. W. Bragby, Attorney

UNITED STATES PATENT OFFICE.

MILTON M. BAGBY, OF DENVER, COLORADO, ASSIGNOR OF ONE-THIRD TO JOHN B. GLASER, OF DENVER, COLORADO.

SASH-STOP.

No. 892,970.

Specification of Letters Patent.

Patented July 7, 1908.

Application filed October 16, 1906. Serial No. 339,222.

To all whom it may concern:

Be it known that I, MILTON M. BAGBY, a citizen of the United States, residing in the city and county of Denver and State of Colorado, have invented certain new and useful Improvements in Sash-Stops; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in stops or holding devices for window sash, whereby the sash may be held in any desired position of adjustment, but at the same time may be easily moved either up or down.

My improved device comprises a spring-actuated pin mounted in the frame adapted to protrude therethrough into a groove formed in the sash and normally engaging a plate which is mounted on said frame, the bottom of this groove having a wave-like corrugated surface, while the engaging extremity of the pin is rounded or curved, thus allowing the sash to be moved up or down as will be readily understood. During the movement of the sash it is evident that the pin has a reciprocating action due to the engagement of the bottom of the groove therewith.

Having briefly outlined my improved construction as well as the function it is intended to perform, I will proceed to describe the same in detail reference being made to the accompanying drawing in which is illustrated an embodiment thereof.

In this drawing, Figure 1 is a front view of a window sash and frame equipped with my improvements and shown partly in section. Fig. 2 is a fragmentary sectional view shown on a larger scale. Fig. 3 is a section taken on the line 3—3 Fig. 2. Fig. 4 is a face view of the frame looking from the inside with the sash removed.

The same reference characters indicate the same parts in all the views.

Let the numeral 5 designate the sash as a whole; 6 the side rails thereof; and 7 the window frame. In each side of this frame is inserted a casing 8 having flanges 9 through which screws 10 are passed for the purpose of

securing the casing to the frame. This casing is open to receive the stop pin 12 which is surrounded by a coil spring 13, one extremity of which engages a shoulder formed in the casing, while the other extremity acts upon a circular rib or collar 14 formed on the pin near its outer extremity. This pin is normally locked in place in the case by means of an outer plate 15 secured to the flanges 9 of the casing by rivets 16. The plate 15 is provided with a central opening 16 through which the operating extremity 12^A of the stop pin protrudes to engagement with the corrugated surface of a plate 17 inserted in a groove 18 formed in the sash rail 6.

The frame may be equipped with dust-excluding strips 19 attached thereto on opposite sides and overlapping the division between the sash and frame. The corrugated plate 17 is secured to the sash by screws 20 or other suitable fastening devices.

From the foregoing description the use and operation of my improved device will be readily understood. Assuming that the device is applied to the frame and sash as illustrated in the drawing and heretofore described, it is evident that the sash may be raised or lowered at will and that the stop pin 12^A will retain the sash in any desired position of adjustment.

Having thus described my invention, what I claim is:

In a device of the class described, the combination of a casing adapted to be inserted in the window frame adjacent the sash, a pin inserted in said casing and provided with a shoulder, a coil spring surrounding the pin and acting on the shoulder to force the latter outwardly through an opening in the casing, and a plate applied to the casing exteriorly and having an opening for the outer extremity of the pin, the said plate normally engaging the shoulder of the pin exteriorly, and a corrugated plate adapted to be attached to the sash and engage the outer extremity of the stop pin which is rounded or curved to facilitate the movement of the sash, substantially as described.

In testimony whereof I affix my signature in presence of two witnesses.

MILTON M. BAGBY.
